(57) **CLAIM**

We claim the ornamental design for a pallet truck, as shown and described.

DESCRIPTION

FIG. 1 is a front left perspective view of a pallet truck handle according to our new design;

FIG. 2 is a front right perspective view thereof;

FIG. 3 is a rear left perspective view thereof;

FIG. 4 is a rear elevational view thereof;

FIG. 5 is a right side elevational view thereof;

FIG. 6 is a front elevational view thereof;

FIG. 7 is a left side elevational view thereof;

FIG. 8 is a top plan view thereof; and,

FIG. 9 is a bottom plan view thereof.

The broken lines shown in the figures are included for the purpose of illustrating portions of the pallet truck and form no part of the claimed design.
